UNITED STATES PATENT OFFICE

IAN MACDONALD, OF MODESTO, CALIFORNIA

DESIGN FOR A TABLE AND SEAT UNIT

Application filed July 5, 1932. Serial No. 44,264. Term of patent 14 years.

To all whom it may concern:

Be it known that I, IAN MACDONALD, a citizen of the United States, residing at Modesto, in the county of Stanislaus and State of California, have invented a new, original, and ornamental Design for a Table and Seat Unit, of which the following is a specification, reference being had to the accompanying drawing, forming part thereof.

In said drawing, Fig. 1 is a top plan view of a table and seat unit, showing my new design, and Fig. 2 is a side elevation of the same.

I claim:

The ornamental design for a table and seat unit, as shown.

IAN MACDONALD.
